SOLVENT EXTRACTION IN SUCCESSIVE OPERATIONS

Warren F. Faragher, Woodbury, N. J., assignor
to Houdry Process Corporation, Dover, Del., a
corporation of Delaware

Application March 7, 1934, Serial No. 714,417

4 Claims. (CL. 196—13)

This invention relates to the production of raffinates and/or extracts from composite materials, especially mineral oils, and distillates, fractions, blends, products and residues thereof. More particularly, it concerns the manufacture of lubricating oils, insulating oils, and other final or intermediate products requiring the selective concentration of certain favorable components and the suppression and/or removal of certain undesirable components.

In solvent refining of lubricating stocks the refiner usually finds that he must sacrifice high yields if he is to produce a raffinate of the highest quality possible of realization with such processes. On the other hand, if he is to hold his production costs, per unit of marketable product, to a reasonable figure, he frequently finds it necessary to sacrifice quality for the sake of a better yield.

One object of the invention is to devise ways and means for effecting a more complete segregation or separation of the desirable and the undesirable components of a given starting material. Another object is a more efficient and economical use of solvents. Another object is to improve the technique of solvent extraction. Still another object is to secure both high yield and high quality of product. Still another object is to change the temperature of operation to more favorable ranges. Still other objects will be apparent from the detailed description which follows.

The invention involves the use of two solvents in distinct and successive operations, rather than concurrently. One solvent is first applied to the starting material and then the other solvent is used on one of the products or extracts from the first solvent operation. For example, in the treatment of a lubricating stock, a selective naphthenic solvent may be used to produce a high viscosity index raffinate, the other extract or reject being then subjected to the action of a second or paraffinic solvent to strip the same of entrained or absorbed paraffins thereby to secure a high total yield of paraffinic constituents suitable for lubricants. The lighter extract or raffinate from the second solvent treatment, comprising paraffins and some of the naphthenes most easily dissolved by the paraffinic solvent, may be inferior to the first raffinate in quality but is still able to meet present day standards for automobile and other lubricants. Recycling or recirculating a part of one of the extracts or group of components may be resorted to in either or both of the above successive solvent operations, to control the relative paraffinicity and naphthenicity of hydrocarbon material being extracted in each, especial-

ly at points illustrated hereinafter, whenever it is advantageous or economical by reason of a still more complete separation of components. In certain instances recycling favorably affects the temperature or range of temperature where the separating action takes place.

In order to illustrate the invention and the manner of its use, concrete embodiments thereof are diagrammatically indicated in the accompanying drawings, in which:

Fig. 1 indicates solvent treatment in successive operations by the use of packed towers;

Fig. 2 indicates multiple stage solvent treatment in successive operations; and

Figs. 3 and 4 are similar to Figs. 1 and 2, respectively, but indicating methods of recycling.

In the countercurrent packed tower or special tray tower system indicated in Fig. 1, the charge oil is admitted into the lower end of the first tower, while a solvent for naphthenes and aromatics, such as phenol, nitrobenzene, certain chlorine derivatives of organic compounds, especially dichlorethyl-ether, or the like, is admitted at the upper end of the tower and passes therethrough countercurrently to the charge oil. The upper extract or raffinate passes off at the top to storage and to solvent recovery, while the lower extract containing the solvent is withdrawn at the bottom of the tower and is passed directly to the top of a second packed or special tray tower, where it moves countercurrent to a solvent for paraffins, such as propane, butane, straight run light naphthas, or the like, admitted at the lower end of the second tower. The paraffinic solvent strips the extract from the first packed tower of most if not all of the desirable components, the latter passing from the top of the second packed tower as a second upper extract or raffinate to be kept in storage or sent to solvent recovery. The final or second lower extract is withdrawn from the bottom of the second packed tower for storage or sent to solvent recovery.

Fig. 2 shows an arrangement for multiple stage solvent treatment in successive operations. While any number of stages may be used, four are indicated in the accompanying drawings. The charge material and the solvents in both operations move in a countercurrent manner through the series of mixing and separating stages. In the first solvent operation, the fresh charge oil is subjected to the action of a solvent for naphthenes and aromatics such as specified in connection with Fig. 1. The charge oil is directed to mixer M—1 of the first mixing and separating stage, while the solvent goes from

storage first to mixer M-4 of the fourth mixing and separating stage. Thus charge oil, mixed with thrice used solvent and extract admitted by line E-3 from the bottom of separator S-2 of the second mixing stage, passes to the first mixing and refining stage. The upper layer or raffinate from separator S-1 passes to mixer M-2 of the second mixing and separating stage along with twice used solvent and extract passing by line E-2 from the bottom of separator S-3 of the third mixing and separating stage. The upper separated layer or raffinate passes from separator S-2 by line R-2 to mixer M-3 of the third mixing and separating stage along with once used solvent and extract passing from the bottom of separator S-4 of the fourth mixing stage by line E-1. Upper layer or raffinate from separator S-3 of the third mixing stage passes by line R-3 to mixer M-4 of the fourth mixing stage together with fresh naphthenic solvent from storage. The final upper layer extract or raffinate passes from separator S-4 of the fourth mixing and separating stage directly to first raffinate storage, whence it may be removed for solvent recovery. The final lower layer extract, composed largely of solvent and the undesirable components of the charge oil, passes from the bottom of separator S-1 of the first separating stage by line E-4 to first extract storage. This completes the first solvent operation.

This final extract from the first operation, which may be called for convenience the first extract, is then subjected countercurrently in a similar group of stages to the action of suitable solvent for paraffines, including any of those mentioned in connection with Fig. 1. Since the movement of the charging stock and of the solvent in the second operation conforms to that already described in connection with the first operation, a detailed recitation of the same is unnecessary, but, to make it clear, the same reference characters are applied to the elements of the second operation as for the first operation, except that the letters are primed. In this second operation, the final or first extract of the first operation is stripped of the desirable components entrained or retained therein, with the result that a final or second raffinate is withdrawn by line R'-4 from the fourth or final mixing and separating stage of the second operation. This second raffinate may be somewhat inferior in quality to the raffinate from the first operation, due to the possible inclusion of a larger quantity of naphthenic or aromatic components.

Figs. 3 and 4 indicate ways in which recycling may be utilized in both countercurrent tower contact systems and multiple stage mixing and separating systems, for the purpose of effecting a still more complete separation of the desirable and undesirable components. It is to be understood that recycling may be used in such systems in either the first solvent operation or in the second solvent operation, or in both operations, as may be found to be most advantageous and economical. Fig. 3 indicates by a heavy black line selective withdrawal of all or a part of the first lower extract and discharge of the same into the upper end of the first packed tower at a point somewhat below the inlet for fresh naphthenic solvent. In the second solvent operation of the system shown in Fig. 3, recycling is effected (see the heavy black line) by taking all or a selected quantity of the second upper extract or raffinate and discharging the same into the lower

end of the second packed tower at a point somewhat above the inlet for the fresh paraffinic solvent.

For the stage solvent system indicated in Fig. 4, recycling may be effected by sending all or a selected portion of the final extract by line C-1, indicated in heavy black, to join line E-1 which conducts once used solvent and extract from separator S-4 to mixer M-3 of the third mixing and separating stage. For the second solvent operation, the raffinate is recycled rather than the extract, line C'-1 (also in heavy black) conducting all or a selected part of the final or second raffinate from line R'-4 to join the lines leading to mixer M'-1 of the first mixing and separating stage, this recycled raffinate being mingled with fresh charge comprising the final extract of the first solvent operation, together with the extract withdrawn from the bottom of separator S'-2 of the second mixing and separating stage.

For systems such as indicated in Figs. 3 and 4, it is preferable to recycle completely until products of the desired quality are obtained and thereafter to effect only a partial recycling while the remainder of the products capable of being recycled are withdrawn, intermittently or continuously, from the system. In certain instances, recycling makes possible a raising of the temperature at which the components separate with the desired composition thereby lowering the cost of refrigeration.

It is to be understood that the terms "desirable" and "undesirable" are used herein in a relative rather than in a limiting sense, and in order to make the terminology conform to common usage in the industry. Both or all of the extracts or groups of components are desirable in the sense that they are convertible into valuable finished products.

While my invention, in referring to the introduction or recycling of strongly naphthenic hydrocarbons in one extraction zone, or equivalent, and to the introduction of strongly paraffinic components in a second extraction zone, or equivalent, is particularly illustrated by recycling products of the process, yet it will be understood that my invention is not to be limited by this specific, preferred illustration but is meant to cover equivalent operations. For example, instead of recirculating particular products of my process, this invention comprehends introducing into the reaction zones, from outside sources, liquids respectively of the approximate composition of recycled liquids hereinabove described, thereby to improve the yield and quality of desired products.

I claim as my invention:

1. In the art of separating a hydrocarbon charging material into desirable and undesirable components by the action of solvents, the operative process which comprises acting on the charging material with a solvent for the undesirable components, removing the desirable components thus separated, then subjecting the solvent mixture containing undesirable components from the first solvent operation to the action of a solvent for the desirable components thereby to strip said mixture of any desirable components retained therein, and during the second solvent operation altering the relative paraffinic and naphthenicity of hydrocarbon material being extracted by introducing a liquid, of at least approximately the composition of the desirable components separated therein, into the zone of

said second extraction operation at a point remote from the point of withdrawal of desirable components therefrom so that the said liquid contacts the hydrocarbon material being extracted in said second solvent operation and moves in counterflow relation with the same.

5 2. In the art of separating a viscous hydrocarbon oil charge into fractions which are relatively more paraffinic and more naphthenic than the original charge, the process which comprises acting on the charge with a solvent for naphthenes in a counter flow operation in a first extraction zone to separate out an extract fraction and a raffinate fraction, recycling a portion 10 of the extract fraction into said extraction zone at a point approaching but spaced from the point of withdrawal of raffinate therefrom, thereby to produce a high quality raffinate which is substantially free of entrained naphthenes, acting 15 on the remaining portion of the extract fraction which is not recycled with a solvent for paraffinic components in a second counter flow extraction zone to strip paraffinic components from said extract fraction, and recycling a portion of 20 the raffinate from this second counter flow operation in counter flow relation with the said extract fraction during at least a substantial portion of the extraction of the latter, so as to increase the yield of paraffinic components in said 25 raffinate fraction.

30 3. In the art of separating hydrocarbon charging material into components which are respectively more paraffinic and more naphthenic than the said charging material by the action of solvents, the operative process which comprises acting on the charging material with a solvent for one of said components in a counter flow extraction operation involving at least one stage to produce two fractions, one of which contains 35 most of the solvent, the hydrocarbon component more soluble therein and a small amount of the other hydrocarbon component, and the second of said fractions being composed principally of said

other or undissolved hydrocarbon component, acting on the first-mentioned or dissolved fraction in a second extraction operation with a different solvent having a selective solvent affinity for the hydrocarbon component present 5 therein in minor amounts to separate out further quantities of the last-mentioned component, in addition to the amounts thereof produced as undissolved fraction in the first extraction operation, and recycling in each of said extraction 10 operations, in counter flow relation to the hydrocarbon charge to each for at least a substantial portion of the extraction of the respective hydrocarbon charge, the product respectively of each 15 operation which predominantly contains the solvent fed to such respective operation, thereby to secure maximum yield and quality of the desired product.

4. In the art of separating a viscous hydrocarbon charging material into two raffinates and 20 a final extract by the action of solvents, the continuous process which comprises acting on the charging material in a first extraction zone with a solvent for naphthenes in a counter flow operation involving at least one stage to separate 25 out a first raffinate and a first extract, acting on the first extract in a second extraction zone with a solvent for paraffins in a second counter flow operation involving at least one stage to separate 30 out a second raffinate and a final extract, recycling a portion of the first extract in the first counter flow operation and introducing it back 35 into said first extraction zone at a point in the extraction circuit adjacent that at which said solvent for naphthenes is introduced thereinto, to improve the quality of the first raffinate, and recycling a portion of the second raffinate in the second counter flow operation and reintroducing it into said second extraction zone at a point in the latter adjacent that at which said solvent for 40 paraffins is introduced thereinto, to secure a high total yield of raffinate.

WARREN F. FARAGHER.
